GAME APPARATUS

Henry B. Scherer, South St. Paul, Minn.

Application June 28, 1935, Serial No. 28,937

1 Claim. (Cl. 273—130)

This invention appertains to new and useful improvements in game apparatus and more particularly to a game played with movable pieces.

The principal object of the present invention is 5 to provide a game board whereon various forms of games can be played involving movable game pieces and whereon means is provided for retaining these game pieces intact when the board is not in use.

10 During the course of the following specification, other important objects and advantages of the invention will become apparent to the reader.

In the drawings:

15 Figure 1 represents a top plan view of the board.

Figure 2 represents an edge elevational view of the board.

Figure 3 represents a longitudinal sectional view through the board.

20 Figure 4 is a transverse sectional view taken substantially on line 4—4 of Figure 1.

Figure 5 represents an end elevational view of the board.

25 Figure 6 is a perspective view of one of the rubber bands.

Figure 7 represents an elevational view of one of the game pieces.

Referring to the drawings wherein like numerals designate like parts it can be seen that the

30 device consists of a board 5 of suitable rectangular dimensions and having displayed on its top surface suitable game markings such as the game

represented which involves an outer rectangle 6, an inner rectangle 7 and a still further inner

35 rectangle 8 with a diamond formation 9 inside of the rectangle 8 and lines extending from the

mid points of the ends of the rectangle 8 to intersect the ends of the rectangle 7 and connect with the ends of the rectangle 6 and further lines ex-

40 tending from the middle of the side portions of the rectangle 8 to intersect the rectangle 7 and connect with the rectangle 6 at the midpoint of its side portions.

45 Longitudinally extending ribs 9 are provided on the board adjacent their longitudinal edge

portions to prevent the game pieces 10 from easily sliding off of the board.

At each end of the game board 5 is located an elongated hood structure 11 the end portions of which are tapered as at 12. At the outer edge portion of each of these hoods 11 a barrel 13 is formed, these hoods preferably being of sheet 5 metal. An elongated rod 14 extends through each of these barrels 13 and is formed with an eye 15 at each end thereof. Eye members 16 are driven into the bore and link with the eye members 15 on the rod 14. Thus a hinged connection 10 is made between the hood 11 and the board 5. Each of the hood members 11 is provided with a finger engageable upstanding lug 17. Under each of the hoods 11 the board is provided with an opening 18 and as is clearly shown in Figure 3, 15 a rubber band 19 is stretched under the board with each end disposed upwardly through the corresponding opening 18 and through a suitable opening in the corresponding hood 11 to engage over a hook 19a on the inner side of the hood. 20 Thus a single rubber band serves to retain both of the hoods snugly against the game board. Under this hood can be arranged the game pieces 10. Obviously, no cover or box is needed for the game board as it is self contained insofar as the 25 retention of the game elements is concerned.

While the foregoing specification sets forth the invention in specific terms it is to be understood that numerous changes in the shape, size and materials may be resorted to without departing from the spirit and scope of the invention as claimed hereinafter.

Having thus described the invention, what is 35 claimed as new is:

A game apparatus comprising a board, a hood structure at each end of the board within which game pieces can be stored, said hood structures being swingably connected to the board along one edge thereof, and an elongated elastic band 40 stretched under the board and having its end portions disposed upwardly through openings in the board to attach to the free edges of the hood structures to retain them downwardly against the board.

45 HENRY B. SCHERER.
